(57) **ABSTRACT**

In a connector, each of housings of a socket and a header serving as connector parts includes: a terminal holder extending in a first direction and includes a terminal section of the associated connector part; and a side wall connector extending in a second direction intersecting the first direction, and connected to one end of the terminal holder of the associated connector part in the first direction. The shield member includes a first portion on the side wall connector, and a second portion aligned with the terminal holder of the connector part in the second direction. The socket and the header are inserted into each other in a third direction intersecting the first and second directions. The second portion of at least one of the shield members includes a shield bent portion with a curved portion curving toward the other connector part to be inserted.

**ELECTRICAL CONNECTOR WITH SOCKET
AND HEADER HAVING MATING
SHIELDING PARTS**

**CROSS-REFERENCE TO RELATED
APPLICATION**

This application claims priority to Japanese Patent Application No. 2019-180690 filed on Sep. 30, 2019, the entire disclosure of which is incorporated by reference herein.

BACKGROUND

The present disclosure relates to a connector and a socket and a header used for the connector.

A typically known connector includes a socket including a plurality of socket-side terminals in a socket body, and a header including a plurality of header-side terminals in a header body (see, e.g., Japanese Unexamined Patent Publication No. 2018-152190).

In the connector described in Japanese Unexamined Patent Publication No. 2018-152190, the connector (i.e., the socket) held by a first substrate and the header held by a second substrate are fitted into each other while facing each other so that the corresponding terminals come into contact with each other to conduct electricity. Accordingly, the circuit patterns of the substrates having terminals connected thereto are electrically connected to each other.

Radio frequency (RF) signals may be applied to terminals of a connector (see, e.g., Japanese Unexamined Patent Publication Nos. 2019-040823 and 2017-033655).

In a fifth generation mobile communication system (what is called a “5G”) that is currently being developed, mounting of multiple antenna elements in various devices is attempted to achieve multiple simultaneous connections, for example.

SUMMARY

However, when RF signals are applied to terminals of a connector, reduction in unnecessary radiation from the terminals and noise mixed into the terminals is required.

When different RF signals are applied to the terminals of the connector, there is a need to reduce the interference between these RF signals.

In view of the typical problems described above, it is an objective of the present disclosure is to reduce unnecessary radiation, noise, and interference between RF signals in a connector to which the RF signals are applied, that is, a socket and a header.

In order to achieve the objective, the present disclosure provides the following configuration. A gap is provided between each of side walls of a socket and a header facing each other and a shield member located outside. The shield member has, in a cross section, a curved portion (or a bent portion) curving toward another shield member to be inserted. In a connector in which the socket and the header are fitted into each other, the shield members of the socket and the header are electrically connected to each other.

Specifically, the present disclosure is directed to a connector, and a socket and a header used for the connector, and provides the following solution.

Specifically, a connector according to one aspect of the present disclosure includes: a socket including a housing, a terminal section, and a shield member; and a header including a housing, a terminal section, and a shield member. The socket and the header serve as connector parts. In each of the connector parts of the socket and the header, the housing

2

includes: a terminal holder extending in a first direction and including the terminal section of an associated one of the connector parts; and a side wall connector extending in a second direction intersecting the first direction, and connected to one end of the terminal holder of the associated one of the connector parts in the first direction. The shield member includes: a first portion on the side wall connector of the associated one of the connector parts; and a second portion aligned with the terminal holder of the associated one of the connector parts in the second direction. The socket and the header are inserted into each other in a third direction intersecting the first direction and the second direction. The second portion of the shield member of at least one of the connector parts of the socket and the header includes a shield bent portion with a curved portion curving toward the other connector part of the socket or the header to be inserted.

According to the present disclosure, unnecessary radiation, noise, and interference between RF signals decrease in a connector to which the RF signals are applied and a socket and header used for the connector.

BRIEF DESCRIPTION OF THE DRAWINGS

FIG. 1 is a perspective view of a connector according to an embodiment of the present disclosure.

FIG. 2 is a cross-sectional view showing pads in the cross section taken along line II-II in FIG. 1.

FIG. 3 is a perspective view of a socket according to the embodiment of the present disclosure.

FIG. 4 is a perspective view of a socket housing according to the embodiment of the present disclosure.

FIG. 5 is a top view of the socket according to the embodiment of the present disclosure.

FIG. 6 is a front view of the socket according to the embodiment of the present disclosure.

FIG. 7 is a right side view of the socket according to the embodiment of the present disclosure.

FIG. 8 is a bottom view of the socket according to the embodiment of the present disclosure.

FIG. 9 is a top view showing the socket on a pad according to the embodiment of the present disclosure.

FIG. 10 is an enlarged partial perspective view of a corner of the socket according to the embodiment of the present disclosure.

FIG. 11 is a perspective view of a header according to the embodiment of the present disclosure.

FIG. 12 is a perspective view of a header housing according to the embodiment of the present disclosure.

FIG. 13 is a top view of the header according to the embodiment of the present disclosure.

FIG. 14 is a front view of the header according to the embodiment of the present disclosure.

FIG. 15 is a right side view of the header according to the embodiment of the present disclosure.

FIG. 16 is a bottom view of the header according to the embodiment of the present disclosure.

FIG. 17 is a top view showing the header on a pad according to the embodiment of the present disclosure.

FIG. 18 is an enlarged partial perspective view of a corner of the header according to the embodiment of the present disclosure.

FIG. 19 is a partial enlarged cross-sectional view of a connection between terminals in a region including side walls of the header and the socket constituting the connector according to the embodiment of the present disclosure.

FIG. 20 is a partial cross-sectional view including the connector constituting a module according to the embodiment of the present disclosure.

DETAILED DESCRIPTION

The connector 10 according to one embodiment of the present disclosure includes a socket 20 and a header 30. The socket 20 includes a socket housing 21, socket terminal sections 22A and 22B, and socket shield members 24A and 24B. The header 30 includes a header housing 31, header terminal sections 32A and 32B, and header shield members 34A and 34B. The socket 20 and the header 30 serve as connector parts. In the connector parts of the socket 20 and the header 30, the housings 21 and 31 include terminal holders 21a and 31a and side wall connectors 21d and 31d, respectively. The terminal holders 21a and 31a extend in a first direction and include the terminal sections 22A and 32A of the connector parts, respectively. The side wall connectors 21d and 31d extend in a second direction intersecting the first direction, and connected to one ends of the terminal holders 21a and 31a of the connector parts, respectively, in the first direction. The shield members 24A and 34A include first portions 24A1 and 34A1 on the side wall connectors 21d and 31d of the connector parts, respectively, and second portions 24A2 and 34A2 aligned with the terminal holders 21a and 31a of the connector parts, respectively, in the second direction. The socket 20 and the header 30 are inserted into each other in a third direction intersecting the first and second directions. The second portion 24A2 or 34A2 of the shield member 24A or 34A of at least one of the socket 20 or the header 30 has a shield bent portion 24f or 34f with a curved portion 242 or 342 curving toward the other connector part of the socket 20 or the header 30 to be inserted.

With this configuration, the second portion of the shield member of at least one of the socket or the header has the shield bent portion with a curved portion curving toward the other connector part of the socket or the header to be inserted. At the shield bent portion, the shield members overlap each other. Accordingly, when radio frequency (RF) signals are applied to the connector, unnecessary radiation from the connector and noise as well as interference between the RF signals decrease.

In the connector according to one embodiment, the second portions 34A2 and 34B2 of the shield members 34A and 34B of the header 30 may overlap the second portions 24A2 and 24B2 of the shield members 24A and 24B of the socket 20, respectively in the second direction.

With this configuration, the corresponding portions of the shield members of the socket and the header overlap each other. This configuration further reduces unnecessary radiation from the connector and noise as well as interference between the RF signals.

In the connector according to one embodiment, the housing 21 or 31 of at least one of the connector parts includes side walls 21b and 21c or 31b and 31c extending in the first direction, and located outside the terminal holder 21a or 31a of the housing 21 or 31 in the second direction. The shield members 24A and 34A may be provided on the side walls.

With this configuration, even when a gap is provided between the shield member and the terminal holder 21a or 31a, the shield member can be reliably held in the housing.

In this case, the shield member 24A on the side walls 21b and 21c may have a shield bent portion 24f in the second portion 24A2.

In this configuration, the elasticity of the shield bent portion improves the shielding effect of the shield member and reduces deformations when fitting the connector parts.

In the connector according to one embodiment, the shield members 24A and 24B of the socket 20 may come into contact with the shield members 34A and 34B of the header 30, respectively.

With this configuration, the shield members of the connector parts have ground potentials, for example.

In the connector according to one embodiment, the shield bent portion 24f or 34f in the second portion 24A2 or 34A2 of the shield member 24A or 34A may include pieces 241a to 241c aligned in the first direction.

This configuration increases the elasticity of the shield bent portion.

In this case, the pieces 241a to 241c may come into contact with the second portion 24A2 or 34A2 of the shield member 24A or 34A of the other connector part.

With this configuration, the shield member with the double-layer structure of the shield bent portion shields the terminal holder, which improves the shielding effect.

In the connector according to one embodiment, the second portions 34A2 and 34B2 of the shield members 34A and 34B of the header 30 may be inserted between the second portion 24A2 of the shield member 24A of the socket 20 and the terminal holder 21a of the socket 20 and between the second portion 24B2 of the shield member 24B of the socket 20 and the terminal holder 21a of the socket 20, respectively.

A part of the terminal holder 21a of the socket 20 may be inserted between the second portions 34A2 and 34B2 of the shield members 34A and 34B of the header 30 and the terminal holder 31a of the header 30.

In this configuration, the second portions of the shield members of the header are inserted between the second portions of the shield members of the socket and the terminal holder of the socket, and the terminal holder of the socket is inserted between the second portions of the shield members of the header and the terminal holder of the header. For this reason, when each of the shield members of the socket and the header has the shield bent portion, the shield members with, at the maximum, a four-layer structure are inserted, which further improves the shielding effect.

In the connector according to one embodiment, each of the second portions 24A2 and 24B2 of the shield members 24A and 24B of the socket 20 has the shield bent portion 24f. Each of the second portions 34A2 and 34B2 of the shield members 34A and 34B of the header 30 has the shield bent portion 34f. The shield bent portions 24f of the second portions 24A2 and 24B2 of the shield members 24A and 24B may be in contact with the respective shield bent portions 34f of the second portions 34A2 and 34B2 of the shield members 34A and 34B.

In this configuration, in each of the socket and the header, the shield members with the four-layer structure are inserted in the second portions of the associated shield members, which further improves the shielding effect.

In the connector according to one embodiment, the shield member 24A or 34A of at least one of the connector parts may include a shield connector 24b or 34b at the corner of the side wall connector 21d or 31d of the at least one of the connector parts. The shield connector 24b or 34b may have a cutout 24c or 34c in the side wall surface of the side wall connector 21d or 31d, and a connection portion 24b1 or 34b1 connecting the first portion 34A1 or 24A1 with the second portion 24A2 or 34A2 together.

In this configuration, the shield connector at the corner of the side wall connector of the connector part has the cutout, which facilitates bending of the shield connector along the corner.

In this case, the socket 20 includes the shield connector 24b, while the header 30 includes the shield connectors 34b facing the shield connectors 24b of the socket 20. In the direction in which the shield connectors 24b and 34b face each other, the connection portion 24b1 or 34b1 of one of the shield connectors 24b or 34b may overlap the cutout 24c or 34c of the other shield connector 24b or 34b.

In this configuration, at least a part of each cutout of one of the connector parts is shielded by the connection portions of the other connector part, which reduces the degradation in the shielding effect caused by the cutouts.

In the connector according to one embodiment, when the shield member has the cutouts and the connection portions, the side wall surfaces may be inner wall surfaces 21d2 and 21e2 of side wall connectors 21d and 21e. The cutouts 24c are cut out in the direction from the inner wall surfaces 21d2 and 21e2 toward the upper wall surfaces 21d3 and 21e3 of the side wall connectors 21d and 21e, respectively. As viewed in the third direction, at the edge and opening of each cutout 24c, an outer edge connected to the edge may form an angle greater than 90°.

This configuration reduces the width of the opening of each cutout, which reduces the degradation in the shielding effect caused by the cutouts.

In the connector according to one embodiment, when the shield member has the cutouts and the connection portions, the side wall surfaces may be outer wall surfaces 31d1 and 31e1 of side wall connectors 31d and 31e. The cutouts 34c are cut out in the direction from the outer wall surfaces 31d1 and 31e1 toward the upper wall surfaces 31d3 and 31e3 of the side wall connectors 31d and 31e, respectively. As viewed in the third direction, at the edge and opening of each cutout 34c, an outer edge connected to the edge may form an angle smaller than 90°.

This configuration reduces the width of the opening of each cutout, which reduces the degradation in the shielding effect caused by the cutouts.

In the connector according to one embodiment, provided on the side wall connectors 21d and 21e of the socket 20 is another shield member 24B separated from the shield member 24A of the socket 20 with slits 24e1 and 24e2 interposed therebetween. Provided on the side wall connectors 31d and 31e of the header 30 is another shield member 34B separated from the shield member 34A of the header 30 with slits 34e1 and 34e2 interposed therebetween. In the first direction, the side wall connectors 21d and 21e of the socket 20 face the side wall connectors 31d and 31e of the header 30, respectively. The slits 34e1 and 34e2 may not overlap the slits 24e1 and 24e2, respectively.

In this configuration, the slits of one of the connector parts are shielded by the shield members of the other connector part, which reduces the degradation in the shielding effect caused by the slits.

In the connector according to one embodiment, each of the first portions 24A1 or 34A1 of the shield member 24A or 34A of at least one of the connector parts may include a first shield 24/1 or a second shield 34/2. The first shield 24/1 covers the side wall surfaces 21d1, 21d2, 31d1, and 31d2 of the side wall connectors 21d and 31d of the connector parts. The second shield 3412 covers the upper wall surfaces 21d3 and 31d3 and the side wall surfaces 21d1, 21d2, 31d1, and 31d2 of the side wall connectors 21d and 31d of the

connector parts. Each of the second shields 3412 is connected to the associated one of the first shields 24/1.

In the connector according to one embodiment, the shield member 24A or 34A of at least one of the connector parts 5 may have projections 34g projecting in at least one of the first or second direction. The projection 34g may come into contact with the shield member 24A or 34A of the other connector part.

In this configuration, the projections in the shield members 10 of the connector part ensure a mechanical and electrical connection with the shield members of the other connector part.

In this case, each of the first portions 24A1 and 24B1 of the shield members 24A and 24B of the socket may include 15 the first shield 24/1 covering the inner wall surface 21d2 or 21e2 of the associated one of the side wall connectors 21d or 21e of the socket 20. Each of the first portions 34A1 and 34B1 of the shield members 34A and 34B of the header 30 may include the second shield 3412 covering the outer wall 20 surface 31d1 or 31e1 of the associated one of the side wall connectors 31d or 31e of the header 30. Each second shield 3412 may include the projection 34g in contact with the associated one of the first shields 24/1.

In the connector according to one embodiment, when 25 each shield member includes the projections, the socket housing 21 may include the side walls 21d and 21e extending in the first direction of the socket 20, and located outside the terminal holder 21a of the socket housing 21 in the second direction. Each of the second portions 24A2 and 30 24B2 of the shield members 24A and 24B of the socket 20 may include a third shield 24/3 covering the inner wall surface 21d2 or 21e2 of the associated one of the side wall connectors 21d or 21e of the socket 20. Each of the first portions 34A1 and 34B1 of the shield members 34A and 34B of the header 30 may include a fourth shield 34/4 covering the outer wall surface 31d1 or 31e1 of the associated one of the side wall connectors 31d or 31e of the header 30. Each of fourth shields 34/4 may include the projection 34g in contact with the associated one of the third shields 24/3.

In the connector according to one embodiment, the second portion 24A2 or 34A2 of the shield member 24A or 34A of at least one of the connector parts is aligned with the terminal holder 21a or 31a of the connector part in the second direction with a gap 51 or 52 interposed therebetween. At least a part of the terminal section 22A or 32A of the connector part may be located in the gap 51 or 52 between the shield member 24A or 34A of the connector part and the terminal holder 21a or 31a of the connector part as viewed in the third direction.

50 This configuration allows a visual check of the quality of soldering, which improves the yield in the soldering process.

In the connector according to an embodiment, in particular, when the slits do not overlap each other, each of the first and second portions 24A1 and 24A2 or 34A1 and 34A2 of the shield member 24A or 34A of the at least one of the connector parts 45 may have the shield terminal 24d or 34d connectable to an external mount body.

With this configuration, the shield members of the connector parts have predetermined potentials.

Embodiment

An embodiment of the present disclosure will be described with reference to the drawings.

(Overview of Connector)

FIGS. 1 and 2 show a connector according to this embodiment.

As shown in FIGS. 1 and 2, in a connector 10 according to this embodiment, a header 30 and a socket 20 are, inside the socket 20, fitted into each other while facing each other. Accordingly, corresponding terminals of the socket 20 and the header 30 come into contact with each other to be electrically connected to each other. The socket 20 and the header 30 are example connector parts.

As shown in FIG. 2, the socket 20 is electrically connected to pads 61, and the header 30 is electrically connected to pads 62. Each of the pads 61 and 62 includes wires on a wiring board or a circuit board, for example.

The socket 20 according to this embodiment includes a first socket shield member (i.e., a shield member) 24A and a second socket shield member (i.e., a shield member) 24B that cover almost the entire periphery of the socket 20. Similarly, the header 30 according to this embodiment includes a first header shield member (i.e., a shield member) 34A and a second header shield member (i.e., a shield member) 34B that cover almost the entire periphery of the header 30.

Now, detailed configurations of the socket 20 and the header 30 will be described with reference to the drawings.

(Configuration of Socket)

FIGS. 3 and 5 show the socket constituting the connector according to this embodiment and the socket shield members that cover the periphery of the socket. FIG. 4 shows the housing of the socket constituting the connector according to this embodiment. As shown in FIGS. 3 to 5, the socket 20 according to this embodiment includes a housing (hereinafter referred to as a "socket housing") 21. The housing 21 includes, for example, a terminal holder (or a bottom plate) 21a in a substantially rectangular planar shape, and side walls 21b, 21c, 21d, and 21e around the terminal holder. The terminal holder 21a has a terminal holding side wall 21b0 that holds a first socket terminal section (i.e., a terminal section) 22A, and a terminal holding side wall 21c0 that holds a second socket terminal section (i.e., a terminal section) 22B.

The side walls 21b and 21c extending along the long sides (i.e., in a first direction) and facing each other along the short sides (i.e., in a second direction) are hereinafter referred to as "socket side walls 21b and 21c" which correspond to the "side walls". On the other hand, the side walls 21d and 21e extending in the second direction, facing each other in the first direction, and connecting the socket side walls 21b and 21c are hereinafter referred to as "socket side wall connectors 21d and 21e" which correspond to the "side wall connectors". The socket side wall connectors 21d and 21e are connected to one end and the other end of the terminal holder 21a, respectively, in the first direction.

Now, a configuration of the socket housing 21 will be described with reference to FIG. 4.

As shown in FIG. 4, the socket side wall 21b has an outer wall surface 21b1, an inner wall surface 21b2, and an upper wall surface 21b3. The inner wall surface 21b2 is located opposite to the outer wall surface 21b1 and closer to the socket side wall 21c than the outer wall surface 21b1. The upper wall surface 21b3 connects the outer and inner wall surfaces 21b1 and 21b2 together.

Similarly, the socket side wall 21c has an outer wall surface 21c1, an inner wall surface 21c2, and an upper wall surface 21c3. The inner wall surface 21c2 is located opposite to the outer wall surface 21c1 and closer to the socket side wall 21b than the outer wall surface 21c1. The upper wall surface 21c3 connects the outer and inner wall surfaces 21c1 and 21c2 together.

The socket side wall connector 21d has an outer wall surface 21d1, an inner wall surface 21d2, and an upper wall surface 21d3. The outer wall surface 21d1 is connected to the outer wall surfaces 21b1 and 21c1 of the socket side walls 21b and 21c. The inner wall surface 21d2 is connected to the inner wall surfaces 21b2 and 21c2 of the socket side walls 21b and 21c. The upper wall surface 21d3 connects the outer and inner wall surfaces 21d1 and 21d2 together and is connected to the upper wall surfaces 21b3 and 21c3 of the socket side walls 21b and 21c.

The socket side wall connector 21d is connected to one end of the terminal holder 21a in the first direction. In the second direction, one end of the socket side wall connector 21d is connected to one end of the socket side wall 21b, while the other end is connected to one end of the socket side wall 21c. The terminal holder 21a is connected to the socket side wall connector 21d between both ends 21d4 of the socket side wall connector 21d. Each end 21d4 of the socket side wall connector 21d projects outward from one end of the terminal holder 21a in the second direction so that the socket side wall connector 21d and the terminal holder 21a form a T-shape. The socket side walls 21b and 21c connected to the socket side wall connector 21d are located outside the terminal holder 21a in the second direction.

Similarly, the socket side wall connector 21e has an outer wall surface 21e1, an inner wall surface 21e2, and an upper wall surface 21e3. The outer wall surface 21e1 is connected to the outer wall surfaces 21b1 and 21c1 of the socket side walls 21b and 21c. The inner wall surface 21e2 is connected to the inner wall surfaces 21b2 and 21c2 of the socket side walls 21b and 21c. The upper wall surface 21e3 connects the outer and inner wall surfaces 21e1 and 21e2 together and is connected to the upper wall surfaces 21b3 and 21c3 of the socket side walls 21b and 21c.

The socket side wall connector 21e is connected to the other end of the terminal holder 21a in the first direction. In the second direction, one end of the socket side wall connector is connected to the other end of the socket side wall 21b, while the other end is connected to the other end of the socket side wall 21c. The terminal holder 21a is connected to the socket side wall connector 21e between both ends 21e4 of the socket side wall connector 21e. Each end 21e4 of the socket side wall connector 21e projects outward from the other end of the terminal holder 21a in the second direction so that the socket side wall connector 21e and the terminal holder 21a form a T-shape. The socket side walls 21b and 21c connected to the socket side wall connector 21e are located outside the terminal holder 21a in the second direction. The portions of the socket side wall 21b connected to the socket side wall connectors 21d and 21e face each other in the first direction with a gap interposed therebetween. Similarly, portions of the socket side wall 21c connected to the socket side wall connectors 21d and 21e face each other in the first direction with a gap interposed therebetween.

Note that the socket housing 21 may be a molded article made of an insulating resin material, for example, a liquid crystal polymer (LCP).

As shown in FIGS. 3 and 5 to 8, the first and second socket terminal sections 22A and 22B are located in the socket side walls 21b and 21c of the socket housing 21, specifically, to face the terminal holding side wall 21b0 of the socket side wall 21b and the terminal holding side wall 21c0 of the socket side wall 21c, respectively.

The first socket terminal section 22A in the socket side wall 21b includes, for example, contacts (i.e., terminals) 22a at both ends of the socket side wall 21b, and three contacts

22b between the contacts 22a. On the other hand, the second socket terminal section 22B in the socket side wall 21c includes contacts 22c, 22d, 22e, 22f, and 22g, for example.

In this embodiment, as an example, what is called radio frequency (RF) signals may be applied to the contacts 22a of the first socket terminal section 22A, while ground potentials may be applied to the contacts 22b. On the other hand, signals with lower frequencies than the radio frequency (RF) signals to be applied to the contacts 22a and ground potentials may be applied to the contacts 22c, 22d, 22e, 22f, and 22g of the second socket terminal section 22B, as appropriate.

Note that any signal including the ground potential may be applied to the contacts 22a to 22g. The contacts 22a to 22g themselves have the same configuration. The configurations are however not necessarily the same in all respects.

Each of the upper surfaces (surfaces facing the header 30) of the contacts 22a to 22g may include a gold (Au) plating layer with a thickness of 0.06 μm or less, for example. Accordingly, it becomes difficult for a solder material to reach the upper surfaces of the contacts 22a to 22g when soldering the lower surfaces (surfaces facing the pad 61) of the contacts 22a to 22g. Since no excessive solder material adheres to the upper surfaces of the contacts, the radio frequency characteristics stabilize.

As shown in FIGS. 2 to 5, the socket housing 21 has a holding wall 21f in a region of the terminal holder 21a between the socket side walls 21b and 21c. The holding wall 21f holds the contacts 22a and 22b of the first socket terminal section 22A extending from the socket side wall 21b toward the socket side wall 21c. The holding wall 21f also holds the contacts 22c to 22g of the second socket terminal section 22B extending from the socket side wall 21c toward the socket side wall 21b. The holding wall 21f is integrally molded with, for example, the socket housing 21, namely, the terminal holder 21a.

In this embodiment, as shown in FIG. 8, the lower parts of the contacts 22a to 22g are located inside holes 21h in the terminal holder 21a of the socket housing 21. In addition, the contacts 22a have a smaller thickness (in a third direction in FIG. 2) than the terminal holder 21a. Thus, as shown in FIG. 2, the lower parts (i.e., the tops) of posts (i.e., terminals) 32a of the header 30 fitted into the socket 20 come into contact with the upper surface of the terminal holder 21a of the socket 20 and stops. That is, the tops of the posts 32a do not interfere with the upper surfaces of the contacts 22a. As a result, the height (in the vertical direction in FIG. 2) of the connector 10 in which the socket 20 and the header 30 are fitted into each other is not affected by the lower parts of the contacts 22a.

Note that the holes 21h that are located in the terminal holder 21a of the socket housing 21 and receive at least the lower parts of the second contacts 22b, for example, fitted therein are not necessarily the holes penetrating the terminal holder 21a. Specifically, the holes may be grooves formed from the upper surface of the terminal holder 21a. However, even when the holes 21h are the grooves, the upper surfaces of the second contacts 22b inside the grooves need to be located lower than the upper surface of the terminal holder 21a. The details of the posts 32a of the header 30 will be described later.

In this embodiment, as shown in FIG. 5, the socket terminal sections 22A and 22B of the socket 20 are located in the two facing socket side walls 21b and 21c, respectively. The configuration is not limited thereto. For example, only one of the socket side walls may have the socket terminal section 22A or 22B. In this case, only one of the header

terminal sections 32A or 32B of the header 30 may be provided in correspondence to the socket terminal section.

(Configuration of Socket Shield Member)

As shown in FIGS. 3 and 5 to 8, the first socket shield member 24A according to this embodiment includes a second portion 24A2 and first portions 24A1. The second portion 24A2 covers the socket side wall 21b of the socket housing 21. Each first portion 24A1 covers a part of the associated one of the socket side wall connectors 21d or 21e. Similarly, the second socket shield member 24B includes a second portion 24B2 and first portions 24B1. The second portion 24B2 covers the socket side wall 21c of the socket housing 21. Each first portion 24B1 covers the rest part of the associated one of the socket side wall connectors 21d or 21e.

Specifically, as shown in FIGS. 5 to 8, the second portion 24A2 of the first socket shield member 24A faces the terminal holding side wall 21b0 of the socket side wall 21b with a gap (i.e., void) 51 interposed therebetween. In addition, each of the first portions 24A1 of the first socket shield member 24A is held by at least a part of the associated one of the socket side wall connectors 21d or 21e. Specifically, one of the first portions 24A1 of the first socket shield member 24A is integrally molded with and fixed to the socket side wall connector 21d. When the socket side walls 21b and 21c are provided, the second portion 24A2 of the first socket shield member 24A may be held by the socket side wall 21b.

Similarly, the second socket shield member 24B faces the terminal holding side wall 21c0 of the socket side wall 21c with a gap (i.e., void) 51 interposed therebetween. Each of the first portions 24B1 of the second socket shield member 24B is held by the rest part of the associated one of the socket side wall connectors 21d or 21e. When the socket side walls 21b and 21c are provided, the second portion 24B2 of the second socket shield member 24B may be held by the socket side walls 21b and 21c. Specifically, the second portion 24B2 of the second socket shield member 24B is integrally molded with and fixed to the socket side walls 21b and 21c.

Now, an example holding structure of the socket shield members will be described with reference to FIGS. 3 and 4. For example, the socket shield member 24A includes a shield connector 24b at each of the connecting points between the socket side wall 21b and the socket side wall connectors 21d and 21e. Each shield connector 24b covers the upper wall surface 21b3 of the socket side wall 21b and the outer wall surface 21d1 or 21e1 of the associated one of the socket side wall connectors 21d or 21e.

Each shield connector 24b is located at one of the corners of the socket side wall connectors 21d and 21e. Each shield connector 24b includes a cutout 24c for bending and a connection portion 24b1. The cutouts 24c are cut out in the direction from the connecting points between the inner wall surface 21b2 of the socket side wall 21b and the inner wall surfaces 21d2 and 21e2 of the socket side wall connectors 21d and 21e, respectively, to the connecting points between the upper wall surface 21b3 of the socket side wall 21b and the upper wall surfaces 21d3 and 21e3 of the socket side wall connectors 21d and 21e, respectively. The connection portions 24b1 face the connecting points between the outer wall surface 21b1 of the socket side wall 21b and the outer wall surfaces 21d1 and 21e1 of the socket side wall connectors 21d and 21e, respectively. The cutouts 24c may be located at the connecting points between the outer wall

11

surface 21b of the socket side wall 21b and the outer wall surfaces 21d1 and 21e1 of the socket side wall connectors 21d and 21e, respectively.

This holding structure also applies to the socket shield member 24B.

As described above, the socket shield members 24A and 24B may be configured in two pieces. Here, the holding regions on the socket side wall connectors 21d and 21e of the socket shield members 24A and 24B have slits 24e1 and 24e2 (i.e., first shield gaps), respectively. This two-piece structure facilitates the processing and assembly of the socket shield members 24A and 24B.

The slits 24e1 and 24e2 between the socket shield members 24A and 24B do not overlap each other in the first direction.

Here, the socket shield members 24A and 24B may be formed as follows. The regions covering the socket side wall connectors 21d and 21e including, for example, the regions of the socket side walls 21b and 21c holding the socket shield members 24A and 24B may be formed by insert molding. The socket shield members 24A and 24B may be formed on the socket housing 21 by press-fitting.

In this manner, the socket shield members 24A and 24B according to this embodiment cover almost the entire peripheries of the socket terminal sections 22A and 22B in the socket 20. This configuration further reduces unnecessary radiation and noise caused by the RF signals.

As shown in FIG. 3, the socket shield members 24A and 24B include a plurality of shield terminals 24d at the lower end of the shield body 24a in at least one of the first or second portion 24A1 or 24A2. The shield terminals 24d are connectable to the circuit board or any other board that is a mount body, when the socket 20 is mounted on the circuit board, for example. Accordingly, the socket 20 is electrically and mechanically connectable to the circuit board, for example, by the shield terminals 24d of the socket shield members 24A and 24B.

These shield terminals 24d may be grounded to, for example, the pad 61 such as a circuit board. In this manner, the socket shield members 24A and 24B include, in a plurality of locations, for example, four locations, the shield terminals 24d for grounding. This reduces the interval between these shield terminals 24d. This configuration further reduces unnecessary radiation and noise caused by the RF signals.

The socket shield members 24A and 24B may be made of a material such as a known metal plate, for example, a metal material such as a copper alloy.

In this embodiment, as shown in FIG. 2, in the socket 20, the outer ends for mounting, of the contacts 22a and 22g are located inside the socket shield members 24A and 24B, respectively. Accordingly, the pad 61 such as a circuit board is also located inside the socket shield members 24A and 24B.

In this configuration, almost the entire peripheries of both the contacts 22a to 22g and the pad 61 such as a circuit board are covered by the socket shield members 24A and 24B, which further reduces unnecessary radiation and noise caused by the RF signals.

Note that the arrangement of the contacts 22a to 22g inside the socket shield members 24A and 24B may be applied to at least the contacts 22a to which the RF signals are applied.

As shown in FIG. 5, the socket 20 according to this embodiment has, as described above, the gap (i.e., void) 51 on each of the surfaces on which the socket side walls 21b and 21c face the socket shield members 24A and 24B. With

12

this configuration, the ends for mounting, of the contacts 22a to 22g are exposed between the socket shield members 24A and 24B and the socket side walls 21b and 21c, respectively, in a top view from the plane facing the header 30, for example. That is, some of the contacts 22a to 22g are visible through the gaps 51.

As shown in FIG. 9, this configuration allows a visual check of the quality of soldering between the pad 61 and the contacts 22a to 22g in the process of soldering therebetween. Accordingly, the yield improves in the soldering process.

As shown in FIGS. 2, 3, and 10, in this embodiment, each of the second portion 24A2 of the first socket shield member 24A and the second portion 24B2 of the second socket shield member 24B has a U-shaped cross section in the direction (i.e., the second direction) perpendicular to the direction in which the socket side walls 21b and 21c extend. Specifically, the second portion 24A2 of the first socket shield member 24A includes a shield body 24a and a shield bent portion 24f.

The shield bent portion 24f of the second portion 24A2 is connected to the shield body 24a and bent to be closer to the socket side wall 21b than the shield body 24a so as to have a curved portion 242 closer to the header 30 to be inserted.

The curved portion 242 of the shield bent portion 24f of the second portion 24A2 has a ridge extending in the first direction. That is, the radius center of the arc of the curved portion 242 is located farther from the header 30 to be inserted (i.e., lower) than the apex (i.e., the ridge) of the curved portion 242. In addition, the curved portion 242 is located at the top of the second portion 24B2 closer to the header 30 to be inserted.

The shield body 24a of the second portion 24A2 has side walls extending in the second and third directions. The shield bent portion 24f of the second portion 24A2 has side walls extending in the second and third directions. The side walls of the shield body 24a and the shield bent portion 24f are connected together via the curved portion 242.

The portion of the socket side wall 21c connected to the socket side wall connector 21d faces the portion of the socket side wall 21c connected to the socket side wall connector 21e in the first direction in a region. In this region, the side walls of the shield body 24a and the shield bent portion 24f face each other with a gap (or a void) interposed therebetween.

Specifically, the first, second, and third directions are orthogonal to each other.

The second portion 24A2 of the shield bent portion 24f includes a plurality of pieces 241a to 241c in the direction (i.e., the first direction) in which the first socket terminal section 22A extends. Slits are provided between adjacent pairs of the pieces 241a to 241c. The pieces 241a to 241c are flexible, that is, bendable. In this embodiment, a second portion 34A2 of the shield bent portion 34f of the header 30, which will be described later, includes no piece but may include a plurality of pieces.

Each first portion 24A1 of the first socket shield member 24A includes a shield body 24a and a shield bent portion 24f. The shield bent portion 24f of the first portion 24A1 is connected to the shield body 24a of the first portion 24A1 and bent from the shield body 24a toward the terminal holder 21a so as to have a curved portion 242 closer to the header 30 to be inserted. Each of the shield bent portions 24f of the first portions 24A1 is fixed to the associated one of the socket side wall connectors 21d or 21e.

The shield body 24a of each first portion 24A1 covers the associated one of the outer wall surfaces 21d1 or 21e1 which is an outer surface of the socket side wall connector 21d or 21e in the first direction. The shield bent portion 24f of each

first portion 24A1 has a side wall (i.e., a first shield 24/1) covering the inner wall surfaces 21d2 and 21e2 of the associated one of the socket side wall connectors 21d or 21e.

In the second portion 24A2 of the first socket shield member 24A, the side wall of the shield bent portion 24f covering the inner wall surface 21b2 at both ends of the socket side wall connectors 21d and 21e in the first direction is referred to as a “third shield 24/3”. The same applies to the first and second portions 24B1 and 24B2 of the second socket shield member 24B.

Similarly, the second socket shield member 24B includes a shield body 24a and a shield bent portion 24f being bent toward the socket side wall 21c.

As shown in FIG. 5, in this embodiment, in each shield connector 24b of the first socket shield member 24A connected to the socket side wall connectors 21d and 21e, as viewed in the third direction (i.e., in a top view), at the edge 24c1 and opening of the associated cutout 24c, an outer edge 24c2 connected to the edge 24c1 forms an angle θ1 greater than 90°. This also applies to the shield connectors 24b of the second socket shield member 24B connected to the socket side wall connectors 21d and 21e.

This configuration reduces the gap of each cutout 24c as compared to the case where the outer edge 24c2 connected to the edge 24c1 forms an angle θ1 smaller than or equal to 90° at the edge 24c1 and opening of the cutout 24c. The employment of this configuration further reduces unnecessary radiation and noise caused by the RF signals.

(Configuration of Header)

FIGS. 11 and 13 show the header constituting the connector according to this embodiment and the header shield members that cover the periphery of the header.

As shown in FIGS. 11 and 13, the header 30 according to this embodiment includes a housing (hereinafter referred to as a “header housing”) 31. The housing 31 includes, for example, a terminal holder 31a in a substantially rectangular planar shape. The terminal holder 31a has a terminal holding side wall 31b that holds a first header terminal section (i.e., a terminal section) 32A and a terminal holding side wall 31c that holds a second socket terminal section (i.e., a terminal section) 32B.

The header housing 31 has side walls 31d and 31e facing each other in the first direction and connecting both ends of the terminal holder 31a. The side walls 31d and 31e are hereinafter referred to as “header side wall connectors 31d and 31e” which correspond to the “side wall connectors”. The header side wall connectors 31d and 31e are connected to one end and the other end of the terminal holder 31a, respectively, in the first direction.

The terminal holder 31a is connected to the header side wall connector 31d between both ends 31d4 of the header side wall connector 31d. Each end 31d4 of the header side wall connector 31d projects outward from one end of the terminal holder 31a in the second direction so that the header side wall connector 31d and the terminal holder 31a form a T-shape.

Now, a configuration of the header housing 31 will be described with reference to FIG. 12.

As shown in FIG. 12, the terminal holding side wall 31b holds the first header terminal section 32A as described above. The terminal holding side wall 31c holds the second header terminal section 32B.

The header side wall connector 31d has an inner wall surface 31d2 and an upper wall surface 31d3. The inner wall surface 31d2 is connected to the terminal holding side walls 31b and 31c. The upper wall surface 31d3 connects the outer

and inner wall surfaces 31d1 and 31d2 together and is connected to the terminal holding side walls 31b and 31c.

Similarly, the header side wall connector 31e has an inner wall surface 31e2 and an upper wall surface 31e3. The inner wall surface 31e2 is connected to the terminal holding side walls 31b and 31c. The upper wall surface 31e3 connects the outer and inner wall surfaces 31e1 and 31e2 together and is connected to the terminal holding side walls 31b and 31c.

Like the socket housing 21, the header housing 31 is also a molded article made of a liquid crystal polymer (LCP) that is an insulating resin material.

As shown in FIGS. 11, 13, and 14, the first header terminal section 32A in the terminal holding side wall 31b includes, for example, posts (terminals) 32a at both ends of the terminal holding side wall 31b, and three posts 32b between the posts 32a. On the other hand, the second header terminal section 32B in the terminal holding side wall 31c includes posts 32c, 32d, 32e, 32f, and 32g, for example.

The posts 32a to 32g themselves have the same configuration (or shape). The configurations are however not necessarily the same in all respects as long as excellent electrical connection is established with the contacts 22a and 22b.

Each of the upper surfaces (surfaces facing the socket 20) of the posts 32a to 32g may include a gold (Au) plating layer with a thickness of 0.06 μm or less, for example. Accordingly, it becomes difficult for a solder material to reach the upper surfaces of the posts 32a to 32g when soldering the lower surfaces (surfaces facing the pad 62) of the posts 32a to 32g. Since no excessive solder material adheres to the upper surfaces of the posts, the radio frequency characteristics stabilize.

(Configuration of Header Shield Member)

As shown in FIGS. 11 and 13 to 16, the first header shield member 34A according to this embodiment includes the second portion 34A2 and first portions 34A1. The second portion 34A2 covers the terminal holding side wall 31b of the header housing 31. Each of the first portions 34A1 covers a part of the associated one of the header side wall connectors 31d or 31e. Similarly, the second header shield member 34B includes a second portion 34B2 and first portions 34B1. The second portion 34B2 covers the terminal holding side wall 31c of the header housing 31. Each of the first portions 34B1 covers the rest part of the associated one of the header side wall connectors 31d or 31e.

Specifically, as shown in FIGS. 13 to 16, the second portion 34A2 of the first header shield member 34A faces the terminal holding side wall 31b with a gap (i.e., void) 52 interposed therebetween. Each first portion 34A1 of the first header shield member 34A is held by the associated one of the header side wall connectors 31d or 31e in a region that is about a half the size of the header side wall connectors 31d and 31e.

More specifically, one of the first portions 34A1 of the first header shield member 34A is integrally molded with and fixed to the header side wall connector 31d.

Now, an example holding structure of the header shield members will be described with reference to FIGS. 11 and 12. For example, the first header shield member 34A includes a shield connector 34b at each of the connecting points between the terminal holding side wall 31b and the header side wall connectors 31d and 31e. The shield connector 34b covers the outer wall surface 31d1 or 31e1 and the upper wall surface 31d3 or 31e3 of the associated one of the header side wall connectors 31d or 31e.

The shield connector 34b includes a connection portion 34b1 and a cutout 34c for bending. The connection portions

15

34b1 connect the outer wall surfaces 31d1 and 31e1 to the upper wall surfaces 31d3 and 31e3 of the header side wall connectors 31d and 31e, respectively. The cutouts 34c are cut out toward the connecting points between the outer wall surface 31d1 and 31e1 and the upper wall surfaces 31d3 and 31e3 of the header side wall connectors 31d and 31e, respectively.

This holding structure also applies to the header shield member 34B.

In this manner, the header shield members 34A and 34B may also be configured in two pieces. In the header side wall connectors 31d and 31e, the first portions 34A1 and 34B1 of the header shield members 34A and 34B have slits 34e1 and 34e2 (i.e., second shield gaps), respectively.

The slits 34e1 and 34e2 between the header shield members 34A and 34B overlap each other in the first direction.

As shown in FIGS. 18 and 3, the cutouts 34c of the shield connectors 34b of the header shield members 34A and 34B overlap the respective connection portions 24b1 of the shield connectors 24b of the socket shield members 24A and 24B. Accordingly, at least a part of each of the cutouts 34c of the header shield members 34A and 34B is shielded by the connection portions 24b1 of the associated one of the socket shield members 24A or 24B, which improves the shielding effect.

Note that the regions covering the header side wall connectors 31d and 31e of the header shield members 34A and 34B, for example, may be formed by insert molding. Alternatively, the socket shield members may be formed by press-fitting.

In this manner, the header shield members 34A and 34B according to this embodiment cover almost the entire peripheries of the header terminal sections 32A and 32B provided in the header 30. This configuration further reduces unnecessary radiation and noise caused by the RF signals.

As shown in FIG. 11, each of the header shield members 34A and 34B includes a plurality of shield terminals 34d. The shield terminals 34d are connectable to the wiring board or any other board that is a mount body, when the header 30 is mounted on the wiring board, for example. Accordingly, the header 30 is electrically and mechanically connectable to the wiring board, for example, by the shield terminals 34d of the header shield members 34A and 34B.

These shield terminals 34d may be grounded to, for example, the pad 62 such as a wiring board. In this manner, the header shield members 34A and 34B include, in a plurality of locations, the shield terminals 34d for grounding. This reduces the interval between these shield terminals 34d. This configuration further reduces unnecessary radiation and noise caused by the RF signals.

Note that the header shield members 34A and 34B may be made of a material equivalent to the socket shield members 24A and 24B, for example, a metal material such as a copper alloy.

In this embodiment, as shown in FIG. 2, in the header 30 as well, the respective outer ends for mounting, of the posts 32a and 32g are located inside the header shield members 34A and 34B. Accordingly, the pad 62 such as a wiring board is also located inside the header shield members 34A and 34B.

In this configuration, almost the entire peripheries of both the posts 32a to 32g and the pad 62 such as a wiring board are covered by the header shield members 34A and 34B, which further reduces unnecessary radiation and noise caused by the RF signals.

16

Note that the arrangement of the posts 32a to 32g inside the header shield members 34A and 34B may be applied to at least, for example, the posts 32a to which the RF signals are applied.

As shown in FIG. 13, the header 30 according to this embodiment has, as described above, the gap (i.e., void) 52 on each of the planes on which the terminal holding side walls 31b and 31c face the header shield members 34A and 34B, respectively. With this configuration, the ends for mounting, of the posts 32a to 32g are exposed between the header shield member 34A and the terminal holding side wall 31b and between the header shield member 34B and the terminal holding side wall 31c, in a top view from the plane facing the socket 20, for example. That is, some of the posts 32a to 32g are visible through the gaps 52.

As shown in FIG. 17, this configuration allows a visual check of the quality of soldering between the pad 62 and the posts 32a to 32g in the process of soldering therebetween. Accordingly, the yield improves in the soldering process.

As shown in FIGS. 2, 11, and 18, in this embodiment, each of the second portion 34A2 of the first header shield member 34A and the second portion 34B2 of the second header shield member 34B has partially a U-shaped cross section in the second direction. Specifically, as shown in FIGS. 13 to 16 and 18, the second portion 34A2 of the first header shield member 34A includes a shield body 34a and a shield bent portion 34f.

The shield bent portion 34f of the second portion 34A2 is connected to the shield body 34a of the second portion 34A2 and is bent to be farther from the terminal holding side wall 31b than the shield body 34a so as to have a curved portion 342 closer to the socket 20 to be inserted.

The curved portion 342 of the shield bent portion 34f of the second portion 34B2 has a ridge extending in the first direction. The radius center of the arc of the curved portion 342 is located farther from the socket 20 to be inserted (i.e., higher) than the apex (i.e., the ridge) of the curved portion 342. In addition, the curved portion 342 is located at the top of the second portion 34B2 closer to the socket 20 to be inserted. The shield bent portion 34f of the second portion 34A2 may be flexible.

The shield body 34a of the second portion 34A2 has side walls extending in the second and third directions. The shield bent portion 34f has side walls extending in the second and third directions.

The side walls of the shield body 34a and the shield bent portion 34f of the second portion 34A2 are connected together via the curved portion 342. The side walls of the shield body 34a are located outside (at both ends of) the side walls of the shield bent portion 34f in the first direction. The side walls of the shield body 34a include a fourth shield 34/4 which will be described later.

Each first portion 34A1 of the first header shield member 34A includes a shield body 34a and a shield bent portion 34f.

The shield bent portion 34f of each first portion 34A1 is connected to the shield body 34a and bent to be farther from the terminal holder 31a than the shield body 34a so as to have a curved portion 342 closer to the socket 20 to be inserted.

The shield bent portion 34f of each first portion 34A1 of the first header shield member 34A has a side wall (or a second shield 34/2) covering the outer wall surface 31d1 or 31e1 of the associated one of the header side wall connectors 31d or 31e.

In the second portion 34A2 of the first header shield member 34A, each shield bent portion 34f covering the outer wall surfaces 31d1 or 31e1 of the associated one of the

header side wall connectors **31d** or **31e** in the first direction is referred to as the “fourth shield **34/4**”.

Similarly, the header shield member **34B** includes a shield body **34a** and a shield bent portion **34f** bent farther from the terminal holding side wall **31c**.

As shown in FIG. 13, in this embodiment, in each shield connector **34b** of the header shield member **34A** connected to the header side wall connectors **31d** and **31e**, as viewed in the third direction (i.e., in a top view), at the edge **34c1** and opening of the associated cutout **34c**, an outer edge **34c2** connected to the edge **34c1** forms an angle θ_2 smaller than 90° . This also applies to the shield connectors **34b** of the header shield member **34B** connected to the header side wall connectors **31d** and **31e**.

This configuration reduces the gap of each cutout **34c** as compared to the case in which the outer edge **34c2** connected to the edge **34c1** forms an angle θ_2 greater than or equal to 90° at the edge **34c1** and opening of the cutout **34c**. The employment of this configuration further reduces unnecessary radiation and noise caused by the RF signals.

(Configurations of Socket and Header Terminal Sections)

Now, a configuration of an electrical connection between the socket terminal section **22** of the socket **20** and the header terminal section **32** of the header **30** will be described with reference to FIG. 19. FIG. 19 shows an enlarged cross-sectional configuration of the region including the socket side wall **21b** and the terminal holding side wall **31b** in FIG. 2.

First, a configuration of the header terminal section **32** will be described.

In FIG. 19, the terminal holding side wall **31b** of the header housing **31** is assumed to extend from its base **31f** in the third direction (e.g., downward). Also, the header terminal section **32** is assumed to extend in the first direction perpendicular to the third direction. In this embodiment, the posts **32a** and **32b**, for example, have the same cross-sectional shape. One of the posts **32a** is thus raised as an example here.

The post **32a** includes a first post extension **32a1** and a second post extension **32a2**. The first post extension **32a1** extends in the third direction. The second post extension **32a2** extends opposite to the third direction (i.e., upward) and faces the first post extension **32a1** with the terminal holding side wall **31b** interposed therebetween.

The post **32a** has a first post end **32a3** in the second direction (i.e., outside the header **30**). The first post end **32a3** leads to a second post end **32a4** via the first post extension **32a1**. On the other hand, the post **32a** has the second post end **32a4** opposite to the second direction (i.e., inside the header **30**). The second post end **32a4** leads to the first post end **32a3** via the second post extension **32a2**. Accordingly, the first post extension **32a1** and the first post end **32a3** are aligned in the second direction with respect to the second post extension **32a2**. In addition, the first post end **32a3** is exposed from the base **31f** in the second direction. As shown in FIG. 19, a distance **D1** from a center line **C** to the first post end **32a3** is longer than a distance **D2** from the center line **C** to the second post end **32a4**. The center line **C** extends in the third direction and equally divides the distance between the first and second post extensions **32a1** and **32a2** into two. Note that the distance here refers to the distance (e.g., the minimum distance) in the second direction with respect to the center line **C** extending in the third direction.

At this time, the second post end **32a4** faces the first post extension **32a1** with respect to the center line **C** with the terminal holding side wall **31b** interposed therebetween. In addition, the post **32a** includes a post connector **32a5** that

connects the first and second post extensions **32a1** and **32a2**. On the other hand, the post **32a** has no portion facing the post connector **32a5** with respect to the center line **C** with the terminal holding side wall **31b** interposed therebetween.

5 Next, a configuration of the socket terminal section **22** will be described.

In FIG. 19, in the socket side wall **21b** of the socket housing **21**, the socket terminal section **22** extends in the first direction in correspondence to the header terminal section **32**. In this embodiment, the contacts **22a** to **22g** have the same cross-sectional shape. One of the contacts **22a** is raised as an example.

The contact **22a** includes a first contact extension **22a1**, a second contact extension **22a2**, and a third contact extension **22a3**. The first contact extension **22a1** extends opposite to the third direction (upward). The second contact extension **22a2** extends in the third direction and faces the first contact extension **22a1**. The third contact extension **22a3** extends opposite to the third direction.

15 The contact **22a** further includes a contact connector **22a4** that connects the second and third contact extensions **22a2** and **22a3**. The contact connector **22a4** is aligned with (located below) the post **32a** of the header **30** in the third direction.

20 The contact **22a** also includes a first contact end **22a5** connected to the first post extension **32a1** via the first and second contact extension **22a1** and **22a2**. That is, the first contact end **22a5** is exposed from the bottom of the socket housing **21** in the second direction.

25 The contact **22a** also has a second contact end **22a6** of the third contact extension **22a3** opposite to the first contact end **22a5**. The second contact end **22a6** curves in the third direction so as to face the second contact extension **22a2** and is in contact with the second post extension **32a2**.

30 With the configuration described above, the second contact extension **22a2** of the contact **22a** is in contact with and electrically connected to the first post extension **32a1** of the post **32a** of the header **30**, for example. At the same time, the second contact end **22a6** of the contact **22a** is in contact with and electrically connected to the second post extension **32a2**.

35 Accordingly, in this embodiment, the contact **22a** of the socket terminal section **22** is connected to the first post extension **32a1** of the second post **32a** of the header terminal section **32**. Therefore, the RF signals input to and output from the first contact end **22a5** of the contact **22a** are input to and output from the first post end **32a3** of the post **32a** mainly through the first post extension **32a1** located outside (in the second direction). That is, the RF signals input from the first contact end **22a5** are output from the first post end **32a3** with a relatively short path.

40 In addition, in the post **32a** of the header terminal section **32**, the distance **D2** from the center line **C** to the second post end **32a4** inside the header **30** (i.e., opposite to the second direction) is shorter than the distance **D1** from the center line **C** to the first post end **32a3** outside the header **30**. The center line **C** extends between the first and second post extensions **32a1** and **32a2**. Thus, even when the first contact **22a** that is a terminal of the socket terminal section **22** and the second post extension **32a2** of the post **32a** are connected at the same time, the signals pass through the second post extension **32a2** with a relatively short path. Accordingly, the signals when the first post extension **32a1** is electrically connected to the first contact **22a** are less affected by the phase difference, for example. As a result, isolation (dielectric isolation) of the RF signals improves and deterioration in the radio frequency characteristics decrease.

In this embodiment, as shown in FIG. 14, a wiring pitch A among the posts 32a to 32g of the header 30 is smaller than a width B of each of the posts 32a to 32g. This allows the connector 10 to have a suitable impedance. For example, the ratio ((B/A)×100) of the width B of each post to the pitch A is set to 60% or less. Then, the impedance of the connector 10 can be matched to 50Ω (i.e., a nominal value). The width of each of the posts 32a to 32g is obtained not at the outer end to be connected to the wiring board, for example, but at the portion extending to the terminal holding side walls 31b and 31c.

(Soldering Portion of Each Shield Member)

Now, example mounting parts of the socket shield members 24A and 24B of the socket 20 according to this embodiment will be described. As shown in FIGS. 3 and 9, the lower ends of the socket shield members 24A and 24B are soldered. Here, all mountable lower end surfaces, that is, the surfaces that can be in contact with the pad 61 being a mount board, of the socket shield members 24A and 24B may be soldered.

Similarly, as shown in FIGS. 11 and 17, as the mounting parts of the header shield members 34A and 34B of the header 30 according to this embodiment, the lower ends of the header shield members 34A and 34B are soldered. Here, all mountable lower end surfaces, that is, the surfaces that can be in contact with the pad 62 being a mount board, of the header shield members 34A and 34B may be soldered.

In this manner, the socket 20 according to this embodiment includes, as the mounting parts, the lower ends of the socket shield members 24A and 24B that substantially cover the periphery of the socket housing 21 including the shield terminals 24d. Thus, even when external stress is applied to the socket 20 or the connector 10 after the soldering, the socket 20 or the connector 10 is hardly peeled off.

The header 30 according to this embodiment also includes, as the mounting parts, the lower ends of the header shield members 34A and 34B that substantially cover the periphery of the header housing 31 including the shield terminals 34d. Thus, even when external stress is applied to the header 30 after the soldering, the header 30 is hardly peeled off.

(Connection Between Socket and Header Shield Members of Connector)

Now, mechanical and electrical connection between the socket shield members 24A and 24B and the header shield members 34A and 34B as the connector 10 will be described with reference to the drawings.

In the connector 10 according to this embodiment, when the header 30 is fitted into the socket 20, the second portions 34A2 and 34B2 of the header shield members 34A and 34B overlap the second portions 24A2 and 24B2 of the socket shield members 24A and 24B in the second direction.

At this time, the second portions 24A2 and 24B2 of the socket shield members 24A and 24B come into contact with the second portions 34A2 and 34B2 of the header shield members 34A and 34B, respectively, in one preferred embodiment.

Specifically, as shown in FIGS. 2, 5, and 13, each of the second portions 34A2 and 34B2 of the header shield members 34A and 34B is inserted into the gap 51 between the second portion 24A2 or 24B2 of the associated one of the socket shield members 24A or 24B of the socket 20 and the terminal holder 21a of the socket 20.

At this time, each of the shield bent portions 24f of the second portions 24A2 and 24B2 of the socket shield members 24A and 24B is in contact with the associated one of the

shield bent portions 34f of the second portions 34A2 and 34B2 of the header shield members 34A and 34B.

When the header 30 is fitted into the socket 20, the outer part of each of the shield bent portions 34f of the header shield members 34A and 34B is in contact with the outer part of the associated one of the shield bent portions 24f of the socket shield members 24A and 24B, which facilitates the fitting. In one preferred embodiment, at least the header shield members 34A and 34B or the socket shield members 24A and 24B are elastic, bendable in the second direction. This reduces deformations of the header shield members 34A and 34B and the socket shield members 24A and 24B at the time of fitting. In addition, the rigidity of the connector 10 itself improves after the fitting of the header 30 into the socket 20.

Each of the terminal holding side walls 21b0 and 21c0 of the socket 20 is inserted between the associated one of the second portions 34A2 or 34B2 of the header shield member 34A or 34B and the associated one of the terminal holding side walls 31b or 31c of the header 30.

When the header 30 is fitted into the socket 20, the first portions 34A1 and 34B1 of the header shield members 34A and 34B overlap the first portions 24A1 and 24B1 of the socket shield members 24A and 24B in the first direction.

Specifically, the first portions 34A1 and 34B1 of the header shield members 34A and 34B are inserted between the first portions 24A1 and 24B1 of the socket shield members 24A and 24B and the holding wall 21f and between the first portions 24A1 and 24B1 and the terminal holding side walls 21b0 and 21c0 of the socket 20, respectively.

In the connector 10 according to this embodiment, for example, the portions of the first socket and header shield members 24A and 34A facing the first socket and header terminal section 22A and 32A, respectively, have, at the maximum, the four-layer structure of the first socket and header shield members 24A and 34A. This configuration further reduces unnecessary radiation and a mixture of noise caused by the RF signals.

The first header shield member 34A may have at least one projection 34g projecting outside the header housing 31. The projection 34g is in contact with the first socket shield member 24A of the socket 20.

Specifically, in each of the first portions 34A1 and 34B1 of the header shield members 34A and 34B, the second shield 34/2 has the projection 34g projecting outward in the first direction. The projection 34g comes into contact with the first shield 24/1 of each first portion 24A1 or 24B1 of the associated one of the socket shield members 24A or 24B.

Similarly, in each of the second portions 34A2 and 34B2 of the header shield members 34A and 34B, the fourth shield 34/4 has the projection 34g projecting outward in the second direction. This projection 34g comes into contact with the third shield 24/3 of the second portion 24A2 or 24B2 of the associated one of the socket shield members 24A or 24B.

This configuration further reduces unnecessary radiation and a mixture of noise caused by the RF signals.

In the socket 20 described above, each of the socket shield members 24A and 24B includes no projection projecting outside the socket housing 21 but may also include at least one projection.

In the connector 10 according to one embodiment, the header shield members 34A and 34B are fitted into the respective gaps between the socket shield members 24A and 24B of the socket 20 and the socket side walls 21b and 21c.

However, the configuration is not limited thereto. The socket shield members 24A and 24B may be fitted in the respective gaps between the header shield members 34A and

21

34B and the terminal holding side walls 31b and 31c. However, in this case, the surfaces of the header terminal sections 32A and 32B facing the header shield members 34A and 34B need to be insulated by an insulating member.

As clear from the top view of the socket 20 in FIG. 5 and the bottom view of the header 30 in FIG. 16, when the header 30 is fitted into the socket 20, the socket side wall connectors 21d and 21e are adjacent and opposed to the header side wall connectors 31d and 31e in the first direction. The slits 24e1 and 24e2 of the shield members 24A and 24B of the socket side wall connectors 21d and 21e do not overlap the slits 34e1 and 34e2 of the shield members 34A and 34B of the adjacent and opposed header side wall connectors 31d and 31e in the first direction in one preferred embodiment.

With this configuration, when the socket 20 and the header 30 are fitted, the positions of the slits 24e1 and 24e2 and the socket and the slits 34e1 and 34e2 of the header 30 are not aligned but shifted. For this reason, in each of the slits 24e1, 24e2, 34e1, and 34e2, unnecessary radiation along the long sides of the connector 10 (in the direction in which the socket side wall connectors 21d and 21e face each other) is shielded by the other shield members 24A and 34A, for example. This configuration reduces unnecessary radiation and a mixture of noise.

(Connector Constituting Module)

FIG. 20 shows a partial cross-sectional configuration of a module (electronic module) 40 including the connector 10 according to this embodiment.

Specifically, the connector 10 according to this embodiment is configured by fitting the socket 20 and the header 30. The socket 20 is, for example, mounted on a plurality of pads 61 on the mounting surface of a circuit board 71 made of a resin. The header 30 is, for example, mounted on a plurality of pads 62 on the mounting surface of a wiring board 72 made of resin.

Here, the module 40 may be a well-known electronic device, for example, a mobile device for mobile communication.

The connector constituting the module 40 includes the socket 20 and the header 30 with at least the features shown in FIGS. 5 and 13.

Specifically, in the socket 20, the socket terminal sections 22A and 22B face the socket shield members 24A and 24B located outside with the respective gaps 51 interposed therebetween. Then, as shown in FIG. 9, at least some of the mounting terminals of the contacts 22a to 22g of the socket 20 become visible.

Specifically, the distal ends of the socket terminal sections 22A and 22B are located in the gaps 51 between the second portions 24A2 and 24B2 of the shield members 24A and 24B of the socket 20 and the terminal holder 21a as viewed in the third direction.

Specifically, in the header 30, the header terminal sections 32A and 32B face the header shield members 34A and 34B located outside with the respective gaps 52 interposed therebetween. Then, as shown in FIG. 17, some of the mounting terminals of the posts 32a to 32g of the header 30 become visible.

Specifically, the distal ends of the header terminal sections 32A and 32B are located in the gaps 52 between the second portions 34A2 and 34B2 of the shield members 34A and 34B of the header 30 and the terminal holder 31a as viewed in the third direction.

As shown in FIGS. 9 and 17, this configuration allows a visual check of the quality of soldering of the contacts 22a to 22g and the posts 32a to 32g to the pads 61 and 62,

22

respectively, in the process of soldering. Accordingly, the yield improves in the soldering process of the contacts and posts.

In addition, the peripheries of the contacts 22a to 22g and the posts 32a to 32g including the respective pads 61 and 62 are covered by the shield members 24A, 24B, 34A, and 34B, which further reduces unnecessary radiation and noise caused by the RF signals.

Note that at least the RF signals may be applied to the contacts inside the socket shield members 24A and 24B. Similarly, at least the RF signals may be applied to the posts inside the header shield members 34A and 34B. Alternatively, the connector 10 herein may handle signals except the RF signals.

15

What is claimed is:

1. A connector comprising:
a socket including a housing, a terminal section, and a shield member;

20 a header including a housing, a terminal section, and a shield member;

the socket and the header serving as connector parts; in each of the connector parts of the socket and the header, the housing including:

25 a terminal holder extending in a first direction and including the terminal section of an associated one of the connector parts; and

a side wall connector extending in a second direction intersecting the first direction, and located in the first direction outside one end of the terminal holder of the associated one of the connector parts in the first direction;

the shield member of the socket and the shield member of the header each including:

30 a first portion on the side wall connector of the associated one of the connector parts; and

a second portion aligned with the terminal holder of the associated one of the connector parts in the second direction;

the socket and the header being inserted into each other in a third direction intersecting the first direction and the second direction;

35 the shield member of the socket being in contact with the shield member of the header;

the second portion of the shield member of each of the socket and the header including:

40 a shield body having a first side wall, and a shield bent portion, and

the shield bent portion of each of the socket and the header including:

45 a curved portion, and

a second side wall facing the first side wall in the second direction and connected to the first side wall via the curved portion.

50 2. The connector of claim 1, wherein the second portion of the shield member of the header overlaps the second portion of the shield member of the socket in the second direction.

55 3. The connector of claim 1, wherein the housing of at least one of the connector parts includes:

a side wall extending in the first direction and located outside the terminal holder of the housing in a direction intersecting the first direction, and

the shield member is provided on the side wall.

60 4. The connector of claim 3, wherein the shield member on the side wall includes the shield bent portion in the second portion.

5. The connector of claim 1, wherein the shield bent portion in the second portion of the shield member includes a plurality of pieces aligned in the first direction.

6. The connector of claim 5, wherein the plurality of pieces come into contact with the second portion of the shield member of the other connector part.

7. The connector of claim 1, wherein the second portion of the shield member of the header is inserted between the second portion of the shield member of the socket and the terminal holder of the socket, and a part of the terminal holder of the socket is inserted between the second portion of the shield member of the header and the terminal holder of the header.

8. The connector of claim 1, wherein the shield bent portion of the second portion of the shield member of the socket comes into contact with the shield bent portion of the second portion of the shield member of the header.

9. The connector of claim 1, wherein the shield member of at least one of the connector parts includes: a shield connector at a corner of the side wall connector of the at least one of the connector parts, the shield connector includes: a cutout in a side wall surface of the side wall connector, and a connection portion connecting the first portion and the second portion together.

10. The connector of claim 9, wherein the side wall surface is an inner wall surface of the side wall connector, the cutout is cut out in a direction from the inner wall surface toward an upper wall surface of the side wall connector, and as viewed in the third direction, at an edge and an opening of the cutout, an outer edge connected to the edge forms an angle greater than 90°.

11. The connector of claim 9, wherein the side wall surface is an outer wall surface of the side wall connector, the cutout is cut out in a direction from the outer wall surface toward an upper wall surface of the side wall connector, and as viewed in the third direction, at an edge and an opening of the cutout, an outer edge connected to the edge forms an angle smaller than 90°.

12. The connector of claim 1, wherein provided on the side wall connector of the socket is another shield member separated from the shield member of the socket with a first shield gap interposed therebetween,

provided on the side wall connector of the header is another shield member separated from the shield member of the header with a second shield gap interposed therebetween, and

in the first direction, the side wall connector of the socket faces the side wall connector of the header, and the second shield gap does not overlap the first shield gap.

13. The connector of claim 1, wherein the first portion of the shield member of at least one of the connector parts includes:

a first shield covering a side wall surface of the side wall connector of the one of the connector parts; and

a second shield covering an upper wall surface and the side wall surface of the side wall connector of the one of the connector parts, and connected to the first shield.

14. The connector of claim 1, wherein the shield member of at least one of the connector parts includes: a projection projecting in at least one of the first direction or the second direction, and the projection comes into contact with the shield member of the other connector parts.

15. The connector of claim 14, wherein the first portion of the shield member of the socket includes:

a first shield covering an inner wall surface of the side wall connector of the socket,

the first portion of the shield member of the header includes:

a second shield covering an outer wall surface of the side wall connector of the header, and

the second shield includes the projection in contact with the first shield.

16. The connector of claim 1, wherein the first portion or the second portion of the shield member of at least one of the connector parts includes: a shield terminal connectable to a mount body.

17. A socket for use in the connector of claim 1.

18. A header for use in the connector of claim 1.

19. A connector comprising:

a socket including a housing, a terminal section, and a shield member;

a header including a housing, a terminal section, and a shield member;

the socket and the header serving as connector parts; in each of the connector parts of the socket and the header, the housing including:

a terminal holder extending in a first direction and including the terminal section of an associated one of the connector parts; and

a side wall connector extending in a second direction intersecting the first direction, and located in the first direction outside one end of the terminal holder of the associated one of the connector parts in the first direction;

the shield member of the socket and the shield member of the header each including:

a first portion on the side wall connector of the associated one of the connector parts; and

a second portion aligned with the terminal holder of the associated one of the connector parts in the second direction;

the socket and the header being inserted into each other in a third direction intersecting the first direction and the second direction;

the shield member of the socket being in contact with the shield member of the header;

the second portion of the shield member of each of the socket and the header including:

a shield body having a first side wall, and

a shield bent portion;

the shield bent portion of each of the socket and the header including:

a curved portion, and

a second side wall facing the first side wall in the second direction and connected to the first side wall via the curved portion;

the shield member of at least one of the connector parts including:

a shield connector at a corner of the side wall connector of the at least one of the connector parts;

the shield connector including:

a cutout in a side wall surface of the side wall connector, and

25

a connection portion connecting the first portion and the second portion together;
 the socket including the shield connector;
 the header including the shield connector facing the shield connector of the socket; and
 in a direction in which the shield connectors face each other, the connection portion of one of the shield connectors overlapping the cutout of the other shield connector.

20. A connector comprising:
 a socket including a housing, a terminal section, and a shield member;
 a header including a housing, a terminal section, and a shield member;
 the socket and the header serving as connector parts;
 in each of the connector parts of the socket and the header, the housing including:
 a terminal holder extending in a first direction and including the terminal section of an associated one of the connector parts; and
 a side wall connector extending in a second direction intersecting the first direction, and located in the first direction outside one end of the terminal holder of the associated one of the connector parts in the first direction;

25

the shield member of the socket and the shield member of the header each including:
 a first portion on the side wall connector of the associated one of the connector parts; and
 a second portion aligned with the terminal holder of the associated one of the connector parts in the second direction;

30

the socket and the header being inserted into each other in a third direction intersecting the first direction and the second direction;

35

the shield member of the socket being in contact with the shield member of the header;

the second portion of the shield member of each of the socket and the header including:
 a shield body having a first side wall, and
 a shield bent portion;

40

the shield bent portion of each of the socket and the header including:
 a curved portion, and
 a second side wall facing the first side wall in the second direction and connected to the first side wall via the curved portion;

45

the shield member of at least one of the connector parts including:
 a projection projecting in at least one of the first direction or the second direction; the projection coming into contact with the shield member of the other connector parts;

50

the housing of the socket including:
 a side wall extending in the first direction and located outside the terminal holder of the housing in a direction intersecting the first direction;

55

26

the second portion of the shield member of the socket including:
 a third shield covering an inner wall surface of the side wall of the socket,
 5 the first portion of the shield member of the header including:
 a fourth shield covering an outer wall surface of the side wall connector of the header, and
 the fourth shield including the projection in contact with the third shield.

21. A connector comprising:
 a socket including a housing, a terminal section, and a shield member;
 a header including a housing, a terminal section, and a shield member;
 the socket and the header serving as connector parts;
 in each of the connector parts of the socket and the header, the housing including:
 a terminal holder extending in a first direction and including the terminal section of an associated one of the connector parts; and
 a side wall connector extending in a second direction intersecting the first direction, and located in the first direction outside one end of the terminal holder of the associated one of the connector parts in the first direction;

25

the shield member of the socket and the shield member of the header each including:
 a first portion on the side wall connector of the associated one of the connector parts; and
 a second portion aligned with the terminal holder of the associated one of the connector parts in the second direction;

30

the socket and the header being inserted into each other in a third direction intersecting the first direction and the second direction;

35

the shield member of the socket being in contact with the shield member of the header;

the second portion of the shield member of each of the socket and the header including:
 a shield body having a first side wall, and
 a shield bent portion;

40

the shield bent portion of each of the socket and the header including:
 a curved portion, and
 a second side wall facing the first side wall in the second direction and connected to the first side wall via the curved portion;

45

the second portion of the shield member of at least one of the connector parts being aligned with the terminal holder of the one of the connector parts in the second direction with a gap interposed therebetween, and at least a part of the terminal section of the one of the connector parts being located in the gap between the shield member of the one of the connector parts and the terminal holder of the one of the connector parts as viewed in the third direction.
